UNITED STATES PATENT OFFICE

HERBERT JACKSON, OF ST HELENS, ENGLAND, ASSIGNOR TO ASSOCIATED TELEPHONE & TELEGRAPH COMPANY, OF CHICAGO, ILLINOIS, A CORPORATION OF DELAWARE

AUTOMATIC SWITCH

Application filed September 22, 1930, Serial No. 483,561, and in Great Britain October 11, 1929.

The present invention relates to automatic switches for use in telephone or like systems and is more particularly concerned with switches of the step-by-step type arranged for operation in two directions. A switch of this type as widely used in automatic telephony is provided with ten levels or rows of bank contacts each comprising ten sets and the switch is first operated in a vertical direction to select the required level and is then rotated to select the appropriate set of contacts in the chosen level. The setting of such a switch is effected by two stepping magnets operating pawl and ratchet gearing, one magnet serving to effect the vertical motion while the other effects the rotary motion. The switch is held in its operated position by a so-called double dog which comprises a pair of mechanically connected detents one engaging in the vertical ratchet teeth and the other in the rotary ratchet teeth. The return of the switch wipers to normal position is then effected by a release magnet which moves the double dog out of engagement with the two sets of ratchet teeth whereupon a spiral spring restores the wipers to normal position in the rotary direction after which they fall to the original position under gravity.

The object of the present invention is to simplify the construction of a switch of this type and reduce its cost by eliminating the necessity for the release magnet. For this purpose it is arranged that when the switch is to be released the rotary magnet is again energized and advances the wipers to a predetermined position in which the double dog is mechanically tripped so that the switch then restores to normal under the action of the cup spring and gravity in the usual manner.

The invention will be better understood from the following description of one method of carrying it into effect which should be taken in conjunction with the accompanying drawings. It will be understood, however, that the arrangement shown is given by way of example only and that various modifications to the circuits and mechanical details could readily be made by those skilled in the

art without exceeding the scope of the invention.

Referring now to the drawings, Figs. 1 and 2 show diagrammatic front and side elevations of the mechanism of a switch of the type considered. Fig. 3 is a circuit of a group selector switch, that is to say one which responds to a single series of impulses and subsequently hunts automatically to find a free line, while Fig. 4 shows a circuit of a connector switch that is to say one which responds to two series of impulses.

Referring first to the mechanical construction shown in Figs. 1 and 2, it will suffice to describe merely the modifications which have been made from the standard switch construction. The double dog 5, which is pivoted about the axis 6 and is usually operated by the release magnet armature engaging the part 7, is provided with projections 8 and 9 engaging with the vertical and rotary ratchet teeth 10 and 16 respectively. In the present construction the double dog is provided with an extended arm 11 which cooperates with the cam member 12 which is secured to the shaft 13 by any suitable means. The member 12 has secured to it by means of the screws 14 a web 15 which is of such dimensions that in the twelfth rotary position of the switch shaft the web engages with the extension 11 to effect the movement of the double dog 5 about the pivot 6 against the tension of the spring 17. The double dog is provided with the usual projection 18 adapted to engage in a slot in a spring 19 associated with the vertical magnet armature. The arrangement is such that after the double dog has been tripped by the web 15 it is held in the position in which the projections 8 and 9 are clear of the associated ratchet teeth until the spring 19 is next raised on the operation of the vertical magnet armature whereupon the projection 18 is released and owing to the action of spring 17 the double dog rotates about its pivot so as to prevent the restoration of the switch. The release motion in the rotary direction is effected in the usual manner under the control of the cup spring 21.

Referring now to the circuit shown in Fig. 3, when the switch is seized over the conduc-

tors + and - a circuit is completed for line relay A over lead DT to earth through the dial tone transformer so that the subscriber receives the usual notification that he may operate the dial. The energization of relay A operates relay B at armature a_1 and relay B at armature b_1 prepares the circuit of the vertical magnet, at armature b_2 connects earth to the release trunk conductor RT to hold the preceding switch and at armature b_3 prepares the testing circuit. No further circuit changes take place until the subscriber transmits the next series of impulses whereupon relay A de-energizes intermittently in accordance therewith and on each de-energization completes a circuit for the upper winding of relay C and the vertical magnet VM in series. Relay C is operated in this circuit and being slow to release remains steadily energized throughout the train of impulses. Magnet VM however responds to each impulse to raise the switch shaft and wipers the corresponding number of steps. The double dog springs DD are carried by the member 5 illustrated in Figs. 1 and 2 and therefore close on the first operation of the vertical magnet and remain closed until the double dog is tripped on the switch being advanced to the 12th rotary position. These springs therefore serve to close a circuit for relay G which at armature g_1 completes a locking circuit for itself and at armature g_2 prepares a circuit for the rotary magnet. When relay C de-energizes at the end of the train of impulses, the rotary magnet circuit is completed and the switch wipers are therefore advanced one step into engagement with the first set of bank contacts in the selected level. The rotary magnet RM also towards the end of its stroke opens the interrupter contacts R thus effecting the de-energization of relay G which accordingly opens the circuit of magnet RM which therefore de-energizes also and again closes the interrupter contacts.

In case the line now connected with is busy, test wiper P will encounter earth and a circuit will again be completed for relay G which will therefore operate and cause the rotary magnet to advance the wipers a further step. This alternate operation of relay G and magnet RM continues until a free line is reached at which time wiper P will no longer find earth and the switching relay H which has previously been short-circuited will be energized in series with relay G which cannot now operate owing to the high resistance of relay H. Relay H at armature h_1 opens the circuit of relay B, at armature h_2 prepares a locking circuit for itself and at armatures h_3 and h_4 disconnects line relay A and connects the wipers through. Relay B is as usual provided with a slug to render it sufficiently slow to release so that earth may be fed back from the succeeding switch over

the test wiper before it is removed at armature b_2 .

The connection may be further extended in any desired manner and when it is to be released the calling party will replace his receiver, the effect of which will be to bring about the removal of earth from the release trunk conductor. Thereupon relay H de-energizes and at armature h_1 completes a circuit extending over armatures a_1 and b_1 , off-normal contacts N, both windings of relay C in series and winding of vertical magnet VM to battery. The lower winding of relay C is of comparatively high resistance so that the vertical magnet VM is unable to operate at this time but relay C re-energizes and at armature c_1 connects earth to the release trunk conductor to guard the switch against seizure until it is restored to normal and at armature c_2 completes a circuit for relay G which thereupon energizes the rotary magnet over armatures c_1 , b_2 and g_2 . Relay G and magnet RM now interact in the manner previously described until the switch reaches the 12th rotary position whereupon the double dog is tripped and springs DD open so as to prevent any further energization of the rotary magnet. The switch is now free to restore in the usual manner and when it reaches its normal position, off-normal springs N are opened and thus relay C is de-energized and the switch is completely restored to its original condition.

In case all the lines in the selected level should be busy the switch wipers would be advanced to the 11th rotary position whereupon the cam springs would be operated. Thereupon at springs S1 the impulsing circuit is opened and the busy hold circuit over lead BH is prepared for the right hand winding of relay B, at springs S2 relay H is short-circuited and earth is connected to the test wiper to operate the overflow meter M which is connected to a contact engaged in the eleventh position and at springs S3 busy tone and busy flash battery from lead BT are connected up in place of dial tone to notify the calling party that he cannot obtain his connection. Release is then effected in the manner previously described when the calling party hangs up thus producing the de-energization of relay B. It may be mentioned that during the normal release movement of the switch the cam springs will be operated momentarily but the circuit is arranged so that this operation shall not produce any undesirable consequences. It may be mentioned also that the web 15 effecting the tripping of the double dog may readily be arranged to effect the direct operation of the cam springs.

Referring now to Fig. 4 which shows a connector switch, when the switch is taken into use, line relay A is energized over the leads + and - and at armature a_1 energizes

- relay B over its lower winding. Relay B thereupon at armature b_1 connects earth to release trunk conductor RT to hold the preceding switches, at armature b_2 prepares a 5 circuit for the rotary magnet RM, at armature b_3 prepares a circuit for the vertical magnet VM, at armature b_4 connects up the test wiper P and at armature b_5 prepares holding circuits for relays F, G and H. 10 When the next series of impulses is transmitted, relay A de-energizes intermittently in accordance therewith and on the first de-energization a circuit is completed over off-normal springs N2 in normal position for 15 the lower winding of relay C and the vertical magnet VM in series. The vertical magnet operates to raise the switch shaft and wipers one step while relay C energizes and being slow remains energized throughout the train 20 of impulses. At armature c_1 relay C completes an alternative circuit for itself and the vertical magnet and subsequent impulses are extended over this circuit after the off-normal springs shift on the first step. At 25 the end of the first train of impulses relay C de-energizes and at armature c_1 transfers the impulsing circuit to the rotary magnet. Consequently the next series of impulses produced by the intermittent de-energization of 30 relay A are routed over armature c_1 , interrupter springs R, double dog-springs DD, (now closed), armatures g_1 , h_3 and b_2 to rotary magnet RM and parallel thereto, upper winding of relay E. Relay E which is rendered slow to release by the slugging effect 35 of its short-circuited lower winding energizes and remains energized throughout the second series of impulses and at armature e_2 closes an alternative circuit for the rotary magnet in place of the original circuit which 40 is opened intermittently at the interrupter springs R. Relay E also at armature e_1 completes an alternative circuit for relay A in case busy relay G should be operated during 45 the rotary movement and at armature e_3 connects relay G to the test wiper. 50 In case the wanted line is busy test wiper P will encounter earth when the wipers come to rest and relay G will therefore be operated. Relay G at armature g_1 opens the impulsing circuit to render any further dialling ineffective, at armature g_2 prepares a locking circuit for itself, at armature g_3 connects up busy tone and busy flash battery and at armature 55 g_4 completes the busy hold circuit for the upper winding of relay B. The calling subscriber on hearing the busy tone will realize that he cannot obtain his connection and will replace his receiver, thereupon effecting the 60 deenergization in turn of relays A and B. A circuit is then completed from earth over armature b_1 , interrupter springs R, double dog springs DD, armature b_2 , upper winding of relay E to battery so that relay E is operated and at armature e_2 completes a circuit 65 for the rotary magnet. Relay C is also operated over both its windings in series to battery through the vertical magnet and at armature c_2 guards the switch against seizure and opens the short-circuit round the lower 70 winding of relay E so as to render this relay quick to release. Relay E now acts as an interrupter relay for the rotary magnet and the wipers are therefore advanced until the twelfth rotary position is reached whereupon 75 the double dog is tripped, the double dog springs DD are opened so as to prevent further operation of the rotary magnet and the switch is restored to normal. Relay C remains energized until off-normal springs N1 80 open and thus ensures that the switch shall not be taken into use prematurely. 85 Consider now the case in which the called subscriber is free when his line is connected with. In this case relay G though it may have been operated during the rotary movement will not be operated when relay E releases and accordingly a circuit will be completed from earth over armatures b_5 and g_2 , left-hand winding of relay H, armatures e_3 and 90 b_4 , test wiper P to battery through the cut-off relay and rotary magnet of the called party's lineswitch. The cut-off relay operates to clear the called line of its normal battery and earth connections and relay H also operates and at armature h_1 locks up over its right-hand winding, at armature h_2 opens the circuit of relay G, at armature h_3 opens the impulsing circuit to render any further dialling 95 ineffective, at armature h_4 connects direct earth to the test wiper to busy the called line, at armatures h_5 and h_6 connects ringing current to the called line and at armature h_7 connects up the ring back condenser so as to give 100 the calling party ringing tone. When the wanted party replies, ring trip relay F is operated owing to the direct current bridge completed across the line and at armature f_1 locks up over its upper winding, at armatures f_2 and f_3 disconnects ringing and switches 105 the speaking leads through and at armature f_4 prepares a circuit for the supervisory lamp CSH. Back bridge relay D is now operated by current flow over the wanted party's line 110 and at armature d_1 opens the circuit of the lamp CSH and at armatures d_2 and d_3 reverses the connections of relay A to conductors + and - for the usual supervisory or 115 metering purposes. 120 At the end of the conversation when the called party replaces his receiver, relay D is de-energized and lamp CSH is lighted so as to give an indication should the called party be held owing to the calling party failing to replace his receiver. When the calling party hangs up, relays A and B are de-energized and release of the switch takes place 125 in the manner described above. According to the invention therefore a very simple modification to the known switch con- 130

struction and circuits enables the release magnet to be dispensed with and moreover the wear on the bank contacts and rotary ratchet teeth tends to be equalized.

5 I claim:

1. In an electromagnetic switch of the type in which a wiper-carrying shaft is elevated a number of steps by a pawl and ratchet mechanism, wherein a second pawl and ratchet

10 mechanism functions to then rotate the shaft to position its wipers upon desired bank contacts, wherein restoration of the shaft to its initial position is brought about by the action of a spring and by gravity, and wherein 15 in the operation of a double dog associated with the vertical and rotary ratchet mechanisms permits the restoration to take place, the combination of actuating means upon the shaft engaging and moving the double dog 20 for the purpose set forth, consequent to a predetermined distance of rotation of the shaft.

2. In an electromagnetic switch mechanism 25 wherein a wiper-equipped shaft is stepped vertically and then rotated to connect its wipers with a desired set of bank contacts by consecutively controlled pawl and ratchet mechanisms, and wherein means is provided for restoring the wipers to normal along the 30 path over which they were set, upon the operation of a double dog, the combination of means on the shaft, which acts upon said double dog to move it, for the purpose set forth, upon movement of the shaft to a predetermined position.

3. In an electromagnetic switch mechanism 40 wherein a wiper-equipped shaft is stepped vertically and then rotated to connect its wipers with a desired set of bank contacts by consecutively controlled pawl and ratchet mechanisms, and wherein means is provided for restoring the wipers to normal along the 45 path over which they were set, upon the operation of a double dog, the combination of means on the shaft for moving said double dog to release the switch, and means enabling the operation of said shaft, after it has already positioned its wipers, to bring said 50 means on the shaft into operative relation with said double dog for the purpose set forth.

4. In an electromagnetic switch wherein a shaft is first moved vertically and is then 55 rotated a variable number of degrees, depending upon the particular circuit or circuits to be closed, and wherein a double dog, when operated, permits retrograde movement of the shaft back from its operated to its initial position, the provision of means on the shaft which mechanically actuates the double dog whenever the shaft is rotated beyond a predetermined number of degrees.

5. In an electromagnetic switch of the 60 type wherein a shaft carrying contact wipers is moved vertically and is then rotated to con-

nect the wipers with a desired contact set, and wherein release of the switch is initiated by a double dog co-operating with the vertical and rotary ratchet mechanism, the combination of means on the shaft for operating said double dog as the shaft is rotated a predetermined number of degrees, and contacts operated by the double dog to prevent the shaft from being rotated further than such predetermined number of degrees.

6. In a switch structure, a shaft, means for moving said shaft endwise and for then rotating it variable distances, means for holding said shaft in its operated positions, and means on said shaft cooperative with said last means consequent to a further rotation of said shaft to disengage said holding means from said shaft to enable the shaft to be restored to its initial position.

7. In an electromagnetic switch mechanism wherein a wiper-equipped shaft is stepped vertically and then rotated to connect its wipers with a desired set of bank contacts by consecutively controlled pawl and ratchet mechanisms, and wherein means is provided for restoring the wipers to normal along the path over which they were set, upon the operation of a double dog, the combination of means for moving said double dog clear of the shaft consequent to the movement of the shaft to a predetermined position.

8. In an electromagnetic switch mechanism wherein a wiper-equipped shaft is stepped vertically and then rotated to connect its wipers with a desired set of bank contacts by 100 consecutively controlled pawl and ratchet mechanisms, and wherein means is provided for restoring the wipers to normal along the path over which they were set, upon the operation of a double dog; the provision of an 105 extension on the double dog and a cooperating cam on the switch shaft which co-act, upon a predetermined movement of the shaft, to move the double dog clear of the shaft to enable its restoration to its initial position.

In testimony whereof I affix my signature.
HERBERT JACKSON.
